UNITED STATES PATENT OFFICE.

BERNARD MANOVILL, OF ST. LOUIS, MISSOURI.

DESIGN FOR A SAVINGS-BANK.

47,929.

Specification for Design.

Patented Oct. 5, 1915.

Application filed July 6, 1915. Serial No. 38,321. Term of patent 7 years.

To all whom it may concern:

Be it known that I, BERNARD MANOVILL, a citizen of the United States, residing at 1239 Clara avenue, St. Louis, Missouri, have invented a new, original, and ornamental Design for a Savings-Bank, of which the following is a specification, reference being had to the accompanying drawing, forming part thereof.

Figure 1 is a plan of a savings bank showing my design; Figs. 2 and 3 are respectively a side and end elevation of the bank.

Referring to the drawings by numerals, 5 designates the base of the bank, which inclines upwardly and inwardly, and whose contour is substantially rectangular. This base represents the terraced building site, and in the one bank of the terrace there are the steps 6. Arising integrally from the crest of the base is the body portion 7 which represents the walls of a house and includes elements representing doors and windows.

The numeral 8 designates the roof which

extends with wide eaves beyond the walls 7. Like the base this roof is substantially pyramidal and terminates in a flat surface through which there is formed a slot 9 for the admission of coins.

Extending upwardly from the roof to one side of the mentioned flat surface is a column representing the chimney 10. This column is hollow and is in open communication with the interior of the structure and is designed for the admission of paper money. The base, certain portions of the walls arising from the base, and the roof, are rendered ornate by disks in relief, and the chimney is cylindrical and in its periphery bears imprints representing a stack of coin.

I claim:

The ornamental design for a savings bank, as shown and described.

BERNARD MANOVILL.

Witnesses:

E. L. WALLACE,
R. G. ORWIG.
